UNITED STATES PATENT OFFICE

154,834

DESIGN FOR A COVER PLATE

Frank G. Bellek, Chicago, Ill., assignor to Bell
Electric Company, Chicago, Ill., a corporation
of Illinois

Application October 16, 1947, Serial No. 141,934

Term of patent 7 years

(Cl. D26—1)

To all whom it may concern:

Be it known that I, Frank G. Bellek, a citizen of the United States, residing at 11143 South Peoria Street, Chicago, in the county of Cook and State of Illinois, have invented a new, original, and ornamental Design for Cover Plates, of which the following is a specification, reference being had to the accompanying drawing, forming part thereof.

Fig. 1 is a front view of a cover plate, showing my new design;

Fig. 2 is a back view of the cover plate;

Fig. 3 is a bottom view of the cover plate; and

Fig. 4 is a horizontal section taken on line 4—4 of Fig. 1.

I claim:

The ornamental design for a cover plate, as shown.

FRANK G. BELLEK.
